UNITED STATES PATENT OFFICE

170,764

WAISTBAND

John Hampson Morgan, Old Southgate, London,
England, assignor to Dunlop Rubber Company
Limited, Birmingham, England, a British cor-
poration

Application November 25, 1952, Serial No. 22,449

Term of patent 14 years

(Cl. D3—32)

To all whom it may concern:

Be it known that I, John Hampson Morgan, have invented a new, original, and ornamental Design for a Waist Band, of which the following is a specification, reference being had to the accompanying drawing, forming a part hereof.

Fig. 1 is a plan view of a waist band showing my new design;

Fig. 2 is a side view thereof; while,

Fig. 3 is a cross-sectional view thereof.

The design unit is shown by means of broken lines and repeats horizontally as indicated.

I claim:

The ornamental design for a waist band, as shown and described.

JOHN HAMPSON MORGAN.
